[57] CLAIM

The ornamental design for an electric saw, as shown and described.

DESCRIPTION

FIG. 1 is a top, front and left side perspective view of an electric saw showing our new design;

FIG. 2 is a front elevational view;

FIG. 3 is a top plan view;

FIG. 4 is a left side elevational view;

FIG. 5 is a right side elevational view;

FIG. 6 is a rear elevational view;

FIG. 7 is a bottom plan view;

FIG. 8 is a top, front and left side perspective view, shown with elements of the work support surface separated and in an alternate condition; and,

FIG. 9 is a top, front and left side perspective view thereof, shown with the work support surface in an alternate condition.

FIGS. 2, and 4-6 have been drawn on an enlarged scale with respect to FIGS. 1, 3, and 7-9.

FIG. 1

FIG. 2

FIG. 3

FIG. 4

FIG. 5

FIG. 6

FIG. 7

FIG. 8

FIG. 9
